UNITED STATES PATENT OFFICE

146,892

DESIGN FOR A TOY CAT OR THE LIKE

Candus R. Bailey, Lewiston, Idaho

Application December 19, 1945, Serial No. 124,858

Term of patent 3½ years

(CL. D34—2)

To all whom it may concern:

Be it known that Candus R. Bailey, a citizen of the United States, residing at Lewiston, Idaho, has invented a new, original, and ornamental Design for a Toy Cat or the like, of which the following is a specification, reference being had to the accompanying drawing, forming a part thereof, in which

Fig. 1 is a front elevational view of a toy cat or the like showing my new design; and

Fig. 2 is a rear elevational view on a reduced scale of the toy cat or the like of Fig. 1.

Fig. 3 is a side elevational view on a reduced scale of the toy cat shown in Fig. 1.

I claim:

The ornamental design for a toy cat or the like, as shown.

CANDUS R. BAILEY,
